CLAIM

The ornamental design for a bridge overhang support bracket, as shown.

DESCRIPTION

FIG. 1 is a front perspective view of a bridge overhang support bracket showing our new design;

FIG. 2 is a rear elevational view thereof;

FIG. 3 is a left side elevational view thereof;

FIG. 4 is a top plan view thereof;

FIG. 5 is a front elevational view thereof;

FIG. 6 is a bottom plan view thereof; and

FIG. 7 is a perspective view of a second embodiment of the design shown in FIG. 1, the only difference residing in the appearance of the diagonal jack member.
